W. GLEDHILL

WEIGHTING MOTION OF LOOMS FOR WEAVING

Filed July 21, 1926

FIG.1.

FIG.2.

INVENTOR:

William Gledhill
by Monroe C. Miller
Attorney.

UNITED STATES PATENT OFFICE.

WILLIAM GLEDHILL, OF BARKISLAND, NEAR HALIFAX, ENGLAND.

WEIGHTING MOTION OF LOOMS FOR WEAVING.

Application filed July 21, 1926, Serial No. 124,040, and in Great Britain July 30, 1925.

This invention relates to a loom weighting motion and has for its chief object to construct same in such manner that in addition to dispensing with all weights it will keep a uniform width of cloth from one end of a piece to the other.

According to this invention means are provided whereby variation in the diameter of the warp beam as it unwinds automatically 10 decreases the tension of the ropes or chains which pass around the necks or ruffles of the warp beam.

In the accompanying drawings:—

Figure 1 is an end view of part of a loom 15 fitted with a weighting motion in accordance with this invention, and

Figure 2 is a similar view showing a modification.

Referring to Figure 1 A indicates a whip roller that is rotatably mounted at each end in an arm *a* which is rigidly fixed on a shaft *a*¹ which extends across the loom and is carried at each end by a bracket *a*² detachably secured on the loom end frame B and formed with recesses *a*³ to enable the shaft *a*¹ to occupy different positions. Each arm *a* is connected to the upper end of a rope or chain *c* which passes around the neck or ruffle *c*¹ at each end of the warp beam C. The lower end of each 20 rope or chain is attached to a bar *c*² that extends across the loom and is cranked near its ends and mounted at each end in a lever *c*⁴. Each of these levers extends across the loom end frame and is pivoted to the front portion thereof at *c*⁵, resistance being offered to the upward movement of each lever by a strong spring *c*⁶. To enable the weight to be taken off the ropes or chains *c* when it is required to turn the beam back, or remove it, 25 the cranked rod *c*² is provided with a handle *c*⁷ which can be turned to raise the rod and so take the tension off the ropes or chains. The device for automatically regulating the tension exerted on the ropes or chains *c* as the 30 warp beam C decreases in size comprises a plate or shoe E. This plate or shoe is pivotally mounted on the upper end of an arm *e* that is shown pivoted at *e*¹ in a bracket *e*² attached to the lever *c*⁴ although it might be bolted or otherwise secured to the loom end frame. Rigidly fixed on the shaft *e*¹ is an arm *e*³ and pivotally attached to such arm is a link *e*⁴ which passes between two plates *e*⁵ and is 35 connected therewith by a bolt and nut *e*⁶. Carried by the plates *e*⁵ is a roller *e*⁷ which is caused to bear against the underside of the lever *c*⁴ by a link *e*⁸ which is hooked at its lower end to a stud *e*⁹ carried by the plates *e*⁵ and adjustably connected at its upper end to an arm *a*⁴ by a nut *e*¹⁰, the said arm *a*⁴ being 40 rigidly fixed on the shaft *a*¹, this construction being the same at each end of the loom. The arms *a* and *a*⁴ provide a lever for which the shaft *a*¹ is the fulcrum. When the warp beam is full the parts occupy the position shown, 45 but as the beam decreases in size the upward turning movement of the arm *a*⁴ is caused by the roller *e*⁷ gradually travelling towards the fulcrum *c*⁵ with the result that the arm *a*⁴ gradually and slightly rises thereby slightly slackening the tension on the rope or chain 50 *c* and automatically decreasing the braking action of the latter on the ruffle of the warp beam. As the roller *e*⁷ moves toward the fulcrum *c*⁵ it permits the lever *a*⁴ to rise under the pressure of the warp beam upon the whip roller A on the ends of the arms *a*. When the lever *a*⁴ rises the lever *c*⁴ is permitted to move down under the pressure of the spring *c*⁶, but instead of 55 this counteracting the relaxing effect upon the brake it is clear proof that the brake is becoming relaxed. The spring *c*⁶ is used to give a flexible grip to the chain *c* around the ruffle and allows the beam to oscillate as 60 the shed opens and closes, and the spring *c*⁶ in expanding shows that the tension on the chain is becoming decreased. The action of the link *e*⁸ on the arm *a*⁴ can be varied by adjusting the position of the plates *e*⁵ in relation to the link *e*⁴ and also by adjusting the position of the link *e*⁴ in relation to the arm *e*³. It could also be further varied by altering the shape of the arm *a*⁴ so that the latter 65 presented more of an incline to the roller *e*⁷. 90

In the modified construction shown in Figure 2 which is intended for use in looms that are fitted with large ruffles *c*⁸, the whip roller A is mounted on arms *a*⁶ that are separate from the arms *a* to which the upper ends of the ropes or chains *c* are connected. In this construction the position of the whip roller can be adjusted in relation to the arms *a* and the warp threads *C*¹ remain in contact with the rod *a*¹ during the lifting and lowering movement of the whip roller A that is brought 100 105

about by the opening and closing of the shed.

What I claim as my invention and desire to secure by Letters Patent in the United States is:—

- 5 1. In a loom weighting motion, the combination with a warp beam, of two levers, a flexible element connecting the levers and having a frictional connection with the beam, one lever having a warp engaging member, a link connection between said levers, and means controlled by the decrease in diameter of the beam for controlling said link connection to swing the levers relatively to one another and slacken said flexible element.
- 10 2. In a loom weighting motion, the combination with a warp beam, of two levers, a flexible element connecting the levers and having a frictional connection with the beam, one lever having a warp engaging member, a link connected with said lever and having a movable connection with the other lever to swing the levers relatively to one another, and means controlled by the decrease in diameter of the beam for moving said link relatively to the
- 15 20 25 3. In a loom weighting motion, the combination with a warp beam, of two levers, a

flexible element connecting the levers and having a frictional connection with the beam, one lever having a warp engaging member, a link connected with said lever and having a movable connection with the other lever to swing the levers relatively to one another, an arm adapted to bear against the beam to be moved by the decrease in diameter of the beam, and a link connection between the arm and firstnamed link to shift the firstnamed link by the decrease in diameter of the beam so as to slacken said flexible element.

4. In a loom weighting motion, the combination with a warp beam, of a lever above said beam, a lever below the beam, a flexible element connecting said levers and having a frictional connection with the beam, the upper lever having a warp engaging member, a link connected to the upper lever and having a sliding connection with the lower lever for swinging the levers relatively to one another, an arm to bear against the beam and to move by the decrease in diameter of the beam, and a link connection between said arm and link.

In testimony whereof I affix my signature.

WILLIAM GLEDHILL.
